UNITED STATES PATENT OFFICE.

JULIUS G. PEGEL, OF BROOKLYN, NEW YORK, ASSIGNOR TO BIGELOW HARTFORD CARPET COMPANY, A CORPORATION OF MASSACHUSETTS.

DESIGN FOR A RUG.

50,028.

Specification for Design.

Patented Dec. 12, 1916.

Application filed October 25, 1916. Serial No. 127,710. Term of patent 7 years.

To all whom it may concern:

Be it known that I, JULIUS G. PEGEL, a citizen of the United States, residing at Brooklyn, in the county of Kings and State of New York, have invented a new, original, and ornamental Design for a Rug, of which the following is a specification, reference being had to the accompanying drawing, forming part thereof.

The drawing illustrates a portion of a rug showing my new design.

I claim:

The ornamental design for a rug, substantially as shown.

JULIUS G. PEGEL.

Witnesses:

LLOYD E. KENNEDY,
DAVID G. BARRY.
